UNITED STATES PATENT OFFICE

167,897

COMBINED SWITCH PLATE AND THERMOMETER PLATE

James C. Hughes, New City, N. Y.

Application June 11, 1952, Serial No. 20,125

Term of patent 14 years

(Cl. D26—13)

To all whom it may concern:

Be it known that I, James C. Hughes, a citizen of the United States, residing at New City, in the county of Rockland, and State of New York, have invented a new, original, and ornamental Design for a Combined Switch Plate and Thermometer Plate, of which the following is a specification, reference being had to the accompanying drawing, forming part thereof.

Figure 1 is a front elevational view of a combined switch plate and thermometer plate, showing my new design;

Figure 2 is a side edge view thereof, and

Figure 3 is a top edge view of the same.

Dominant features of my design reside in the portions shown by full lines.

I claim:

The ornamental design for a combined switch plate and thermometer plate, as shown and described.

JAMES C. HUGHES.
